DESIGN FOR A RING

Alexander Klein, New York, N. Y.

Application September 29, 1944, Serial No. 115,524

Term of patent 3½ years

(Cl. D45—10)

To all whom it may concern:

Be it known that I, Alexander Klein, a citizen of the United States of America, residing in New York city, county of New York, and State of New York, have invented a new, original, and ornamental Design for a Ring, of which the following is a specification, reference being had to the accompanying drawing, forming part thereof.

Fig. 1 is a perspective view of a ring showing my new design, Fig. 2 is a perspective view of the opposite side of the ring.

I claim:

The ornamental design for a ring, substantially as shown.

ALEXANDER KLEIN.
